MONUMENT MOLD

Filed June 17, 1931

UNITED STATES PATENT OFFICE

ROBERT R. KOCH, OF RAMSEY, NEW JERSEY, ASSIGNOR TO EVERLASTING MEMORIAL ASSOCIATION OF RIDGEWOOD, NEW JERSEY, A CORPORATION OF NEW JERSEY

MONUMENT MOLD

Application filed June 17, 1931. Serial No. 545,005.

This invention relates to a mold and particularly to a monument mold.

One of the primary objects of my invention is to provide a mold having certain parts adjustable permitting the production of monuments of varying sizes and shapes, depending on the desire of the maker.

Another object is to provide a mold capable of producing monuments in a substantially finished condition in the mold and which monuments will not require subsequent labor for the purpose of curing surface defects.

Other objects and advantages of my device will appear from the more detailed description and the drawing in which like reference characters denote like parts.

Figure 1 is a perspective view of the assembled mold;

Figure 2 is a horizontal cross-sectional view of the mold taken on line 2—2 of Figure 3;

Figure 3 is a vertical sectional view of the mold taken on line 3—3 of Figure 2, and showing the header member in one of its various positions; and

Figure 4 is a perspective view of the header member removed from the mold.

My mold comprises two side walls 10 and two end walls 12 of substantial width, positioned between the ends of the side walls. To the outer surfaces of these side and end walls are securely attached elongated members 14, the ends of which extend beyond the edges of the side and end walls, and having slots 16 formed therein extending inwardly from the outer ends thereof. These members 10, 12 and 14 may be of any desired material having the required strength and rigidity to carry the weight of the molded material and added pressure of packing. They are preferably made of wood because of its strength and cheapness, but other materials may be substituted. Long bolts 18 are adapted to be placed within the slots 16 for holding the two end members and the two side members together. Each of these bolts is provided with a nut 20 on one end and a wing nut 22 threaded on the other end.

50 Washers may be placed inwardly of the nuts

and preferably blocks, such as 24, are placed inwardly of the washers. These blocks engage the outer surfaces of the elongated members 14, to distribute the pressures exerted by the bolts over substantially the entire width of the members 14 and to prevent wear thereof by the nuts and washers.

The side and end walls 10 and 12 are covered on their inner surfaces by linings 26 which extend for the full height of these walls, and for substantially the full width thereof. These linings 26 may be made of metal, such as zinc or any other suitable material having a hard smooth surface. It will be noted that the upper and lower ends of these linings are bent over the upper and lower edges of the walls 10 and 12 and may be secured thereto in any desired manner. It is apparent that the walls may be given a hard smooth, water-repellant surface by other means than by the provision of metallic linings. Also attached to the inner surfaces of end walls 12 and extending along the vertical edges thereof for substantially the entire height, are triangularly shaped corner members or fillets 28. These corner members extend slightly beyond the vertical side edges of the end walls and are preferably made of very fine grained wood or similar material,

which is somewhat compressible and resilient but has sufficient body thereto to enable them to maintain their general form without substantial distortion. While these corner pieces 28 are shown as being of substantially triangular form in cross section, it will be apparent that this form may be varied so as to give the corners of the monument any desired shape or form.

A header member 30 is provided which is adapted to be placed between the sides and ends of the mold for giving the top of the monument any desired form. This header member comprises a substantially flat piece of wood or similar material 32, on at least one face of which is secured a metal lining 34, to which may be secured four substantially wedge-shaped pieces 36, of wood or similar somewhat resilient and compressible material having a smooth surface. The lining 34 is made of lesser area than the surface of the

member 32 so that the edges of the lining do not extend out to the sides of the member 32.

The members 32 and 34 are preferably made substantially rectangular with the corners cut off so as to form, in the example shown, an eight-sided figure exactly fitting within the area enclosed by the members 10, 12 and 28 of the mold body. The outer surfaces of the members 36 constitute prolongations of the outer surfaces of the member 32 throughout the entire periphery thereof. These members 26 taper inwardly and downwardly but do not cover the entire surface of the lining 34, leaving a substantially rectangular portion in the center thereof exposed to form a smoother surface on the top of the monument. The members 36 closely abut each other at the corners, and furthermore, are cut away at the upper corners where they meet to enable them to fit more closely against the corner pieces 28. This header member 30 is made of such dimensions that it is slightly wider than the end walls 12 and also slightly longer than the difference between the length of the side walls 10 and the thicknesses of the end walls 12.

A mold as above described is preferably assembled in the following manner:

The side and end walls are positioned relative to each other and loosely secured in position by the bolts 18. The header member 30 is then placed between the walls of the mold. The end walls 12 are drawn toward each other by the bolts 18 until they lightly contact with the ends of the header member sufficiently to set up a frictional force between the surfaces of the walls and the ends of the header member just sufficient to support the header member in position against the action of gravity. The header member is then moved and adjusted to its desired position intermediate the height of the mold. The end walls are then forced tightly against the ends of the header member by tightening the bolts 18 to clamp the header member in its adjusted position. The bolts 18 securing the side walls to each other are then tightened to force the sides against the corner members 28 and the header member 30 to slightly compress the corner members and the header member. Thus a tight joint is formed at the corners and concrete prevented from flowing between the surfaces of the side walls and the corner members. This tightening of the bolts securing the side walls together causes said walls to form a tight joint with the header member to prevent concrete from flowing between the surfaces of the side walls and the header member, and also to more securely clamp the header member in its desired adjusted position. The clamping of the header member between the end walls before bringing the side walls into contact with the header member, prevents friction between the sides of the end walls and the corner pieces

and the surfaces of the side walls, which friction would hinder the proper tightening of all the walls against the header member.

Thus the mold is more quickly and easily assembled without danger of injuring the corner members. If the side walls were first tightened against the header member, the end walls could not be properly tightened and, on attempting to tighten the end walls, the corner members would probably be injured.

The purposes and advantages of the above described features of construction heretofore described will now be pointed out.

After a monument has been formed in a mold and is ready to be removed therefrom, the wing nuts 22 are unscrewed to loosen the bolts 18 so that they can be removed from the slots in the members 14. The sides, ends and header member may each be separately removed from the monument along lines perpendicular to the surface contacting therewith to leave the monument in a substantially finished condition. The monument may then be lettered or otherwise ornamented as desired while it is still in a slightly plastic condition. By providing the side and end walls with linings or hard, smooth water-repellent surfaces and by making them separately removable from the monument as described, all crazing of the surface of the monument is substantially prevented and no trowelling or other labor is necessary to give the monument its desired finished appearance.

When the side walls 10 are drawn toward each other by the bolts 18, they will contact with the corner members 28, slightly compressing such corner members and forming a close joint so that concrete cannot get between the corner members 28 and the sides or linings 26. Thus the provision of the corner members 28 of slightly resilient material extending beyond the side edges of the end members 12 enables the vertically extending corners of the monument to be made sharp and clear and no trowelling or other labor is necessary to put them in finished condition.

The securing of the corner members 28 to the end walls 12 and the making of the end walls of substantial thickness, enables these end walls to be positioned different distances apart. One extreme position of the end walls is shown in Figure 2, wherein the members 14 secured to the end walls 12 abut against the ends of the side walls 10. The other extreme position of the end walls will be where the inner surfaces thereof are positioned just slightly inwardly of the ends of the side walls 10. Obviously these end walls may be placed at any intermediate position. When the distance between the end walls is varied to any substantial extent, a different size of header member must be provided. However, this header member must be of such proportions that its length, together with the thickness of the two end walls 12, is slightly greater

than the width of the side walls 10. This proportion between the size of the header member and the size of the members forming the side and end walls of the mold must be maintained in order that this header member may be maintained in its desired position within the mold solely by friction upon the surfaces of the side and end walls of the mold.

10 The members 32 and 36 are made of slightly resilient material so that they may be slightly compressed when the walls are tightened against them. This will prevent concrete from getting between the edges of the members 36 and the linings 26 and corner pieces 28 to form unsightly corners. Accordingly, when the bolts 18 are placed in position and the wing nuts thereon tightened, the ends and sides of the mold will be drawn against the 15 ends and sides of the header member so as to firmly clamp it in position and form a tight joint between the edges of the members 36 and the surfaces of the linings 26 and the corner members 28. This causes the 20 various edges and corners of the monument to be clean and clear cut so that subsequent labor, such as trowelling, will not be necessary upon the monument after it has been removed from the mold. The header member being 25 held in position solely by friction of the ends and sides thereof with the surface of the linings 26, it will be appreciated that this header member may be moved to any desired position within the mold so as to form a monument 30 of any desired height.

It will be apparent that molds may be made having sides of different lengths and ends of different widths and thickness than those disclosed in the drawing which are for the purpose of illustration only. For obtaining a monument having any desired proportions, the ends of one mold may be substituted for the ends of another mold so as to vary the thickness and width of the monument produced thereby.

While I have described and shown a specific embodiment of my invention, it is to be understood that such showing and description is merely by way of illustration and that the 50 various parts may be changed in size and form, as will readily appear to one skilled in the art, without departing from the spirit and scope of my invention, as set forth in the following claims:

55 I claim:

1. A mold of the class described comprising side walls of a predetermined length, end walls of a predetermined width and thickness positioned between the ends of the side walls, a removable header member positioned between the said walls and having a shape conforming to the area bounded by said walls, said header member being slightly wider than the end walls and slightly longer than 60 the length of a side wall less the thickness of 65

the end walls but shorter than the total length of a side wall, and means for forcing the walls against the sides and ends of the header member whereby the side walls will contact with the sides of the header member before contacting with the sides of the end walls and the end walls will contact with the ends of the header member before reaching their innermost positions.

2. The method of assembling a mold having side and end walls and a header member which comprises placing the end walls between the ends of the side walls at opposite ends thereof, securing the walls loosely and adjustably together, placing the header member between the walls, moving at least the two end walls toward each other sufficiently to lightly bear against the ends of the header member to set up sufficient friction to support the member against the force of gravity, moving the header member to its desired position, forcing the end walls tightly against the ends of the header member and securing them in position, then forcing the side walls tightly against the sides of the header member and securing them in position.

In testimony whereof, I have signed my name to this specification this 12th day of June, 1931.
